F i g. 5

FIG. 1 is a perspective view of a paddle wheel water-craft embodying our new design;

FIG. 2 is a top plan view of the same;

FIG. 3 is a central longitudinal sectional view taken on the line 3—3 of FIG. 2;

FIG. 4 is a view in side elevation, the opposite side thereof being substantially the same in appearance; and

FIG. 5 is a bottom plan view of the same.

We claim:

The ornamental design for a paddle wheel water-craft, substantially as shown and described.
